UNITED STATES PATENT OFFICE

THEODORE R. CARLSON AND VICTOR A. GRONBERG, OF JAMESTOWN, NEW YORK, AS
SIGNORS TO POSTINDEX COMPANY, INC., OF JAMESTOWN, NEW YORK, A CORPORA-
TION OF MASSACHUSETTS

CHANGEABLE EXHIBITOR

Application filed May 12, 1931. Serial No. 536,742.

This invention relates to changeable exhibitors, having hinged leaves to receive the matter to be exhibited, which may be interchangeable slips, indexes, or other cards. In the example shown, the exhibitor is rotatable, but the invention is not necessarily limited in this respect.

The invention will best be understood by reference to the following description, when taken in connection with the accompanying drawings of one specific embodiment thereof, while its scope will be pointed out more particularly in the appended claims.

In the drawings:

Fig. 1 is a plan of an exhibitor exemplifying the invention;

Fig. 2 is a sectional view on line 2—2 of Fig. 1;

Fig. 3 is a sectional view on an enlarged scale of a portion of Fig. 2;

Fig. 4 is a sectional view on line 4—4 of Fig. 3; and

Fig. 5 is a sectional view on line 5—5 of Fig. 3.

Referring to the drawings, and to the embodiment of the invention which is illustrated therein, there is shown an exhibitor comprising a series of leaves 10, each of which, as herein shown (see Fig. 3) is generally rectangular, and is pivotally mounted on one or more, herein two hinge-pieces 11, as by providing a pintle in the form of a wire 12 (see Fig. 5), which is received in the fold of a metallic strip or bar 13, whose sides embrace the adjacent marginal portion of the leaf. This strip is notched, or cut away as at 14, to receive the hinge pieces 11, each of which is conveniently in the form of a piece of sheet metal folded about the pintle (see Fig. 4), and having its sides 15 brought together face to face.

Each hinge-piece is received in a slot 16, presented by a support, herein comprising a plate 17, which in the case of a rotary exhibitor as herein shown, is bent into cylindrical form. Thus, each plate is of the nature of a drum, provided with a large number of equally spaced slots 16 for corresponding hinge-pieces. Each hinge-piece has appropriate means interlocking with its support, and re-

movable from such interlocking relationship by moving the hinge-piece, first lengthwise of the slot (herein upwardly), and then outwardly therefrom, this being conveniently accomplished in the present example by forming the hinge piece to present a head 18 and a neck 19 connecting the head to the body of the hinge piece, thus providing abutments 20 on the inner face of the supporting plate 17, and abutments 21 on the outer face of the plate. The lower edge of the neck 19 normally rests at the lower end of the slot 16, and the vertical extent of the slot is such that it will accommodate the head 18,—that is to say, when the hinge-piece is lifted the proper distance, the head may be withdrawn outwardly from the slot. In other words, each hinge-piece normally is interlocked with the support, and is retained in such interlocking relationship by gravity, but may be quickly and conveniently removed and replaced, thereby enabling the panels to be interchanged at will.

One important feature of this hinge mounting of the leaves is that the pintles may be very small in diameter, the hinge pieces quite thin, and the slots rather closely spaced, the entire assembly being such that the leaves may be opened up (see the lower portion of Fig. 1) very widely, much more so than is usual with exhibitors of this class.

As herein shown, the plates 17, bent into the form of cylindrical or ring-like supports, are conveniently mounted on upper and lower circular plates or heads 22, connected to each other and spaced apart by a set of rods 23 and a central tubular spacer 24, which is disposed about a vertical shaft 25, there being usual upper and lower bearings 26 and 27, to support the rotating structure on and about the shaft.

Having thus described one embodiment of the invention, but without limiting ourselves thereto, what we claim and desire by Letters Patents to secure is:

1. In a changeable exhibitor, the combination of a support provided with a laterally disposed, vertical slot, a hinge-piece removably received in said slot, a leaf and a pintle

hingedly to said hinge-piece connecting said leaf to said hinge-piece.

2. In a changeable exhibitor, the combination of a support provided with a series of parallel, vertical slots, a series of hinge-pieces removably received in said slots, respectively, a series of leaves, and a pintle hingedly connecting said leaves to said hinge-pieces, respectively.

10 3. In a changeable exhibitor, the combination of a support provided with upper and lower vertical slots, separate upper and lower hinge-pieces received in said upper and lower slots, respectively, and simultaneously removable therefrom by movement in their own plane a rigid leaf, and a pintle hingedly connecting said leaf to said hinge-pieces.

4. In a changeable exhibitor, the combination of a support provided with upper and lower series of vertical slots, each having a closed, lower end, upper and lower series of hinge-pieces removably received in said upper and lower series of vertical slots, respectively, and supported by said ends, and a series of rigid leaves, and pintles, each hingedly connecting one of said leaves to one pair of said upper and lower hinge-pieces.

5. In a changeable exhibitor, the combination of a support having upper and lower sets of slots, upper and lower sets of hinge pieces received in said upper and lower sets of slots, respectively, and interlocking with said support, and a series of leaves, each hinged to said upper and lower hinge pieces.

35 6. In a changeable exhibitor, the combination of a support having upper and lower slots, upper and lower hinge-pieces received in said upper and lower slots, respectively, and having means interlocking with said support and removable from such interlocking relationship by moving said hinge-pieces first upwardly in said slots and then outwardly therefrom, and a leaf hinged to said upper and lower hinge-pieces.

45 7. In a changeable exhibitor, the combination of a support having opposite faces and a slot from one face to the other, a hinge-piece extending from one face of said support, through said slot to the other face of said support, said hinge-piece having abutments cooperating with said faces, respectively, normally to prevent withdrawal of said hinge-piece from said slot, said hinge-piece being movable in said slot to another position in which it may be withdrawn from said slot, and a leaf hinged to said hinge-piece.

8. In a changeable exhibitor, the combination of a support comprising a wall having a vertical slot therethrough, a hinge-piece 60 comprising a body having a shoulder on one side of said wall, a neck extending through said slot, and a head on the other side of said wall, said shoulder and head normally preventing horizontal movement of said hinge-piece in said slot, the vertical extent of said

slot being such that when said hinge-piece is moved upwardly a predetermined distance, said head can be withdrawn horizontally through said slot, and a leaf hinged to said hinge-piece.

9. In a changeable exhibitor, the combination of a support having opposite faces and upper and lower vertical slots extending from one face to the other, upper and lower hinge-pieces associated with said slots, respectively, each hinge-piece comprising a body having a shoulder on one face, a neck extending through the associated slot and a head on the other face, said shoulder and head normally preventing horizontal movement of such hinge-piece in such slot, the vertical extent of each slot being such that when said hinge-pieces are moved upwardly a predetermined distance, said heads can be withdrawn horizontally through said slots, respectively, and a leaf hinged to said hinge-pieces.

In testimony whereof, we have signed our names to this specification.

THEODORE R. CARLSON.
VICTOR A. GRONBERG.

CERTIFICATE OF CORRECTION.

Patent No. 1,845,700.

Granted February 16, 1932, to

THEODORE R. CARLSON ET AL.

It is hereby certified that error appears in the printed specification of the above numbered patent requiring correction as follows: Page 2, line 1, claim 1, strike out the words "to said hinge-piece"; and that the said Letters Patent should be read with this correction therein that the same may conform to the record of the case in the Patent Office.

Signed and sealed this 22nd day of March, A. D. 1932.

**M. J. Moore,
Acting Commissioner of Patents.**
